UNITED STATES PATENT OFFICE.

ALBERT F. HENDERSON, OF MIDDLETON, MASSACHUSETTS.

SURGICAL PATCH.

Application filed May 25, 1921. Serial No. 472,409.

To all whom it may concern:

Be it known that I, ALBERT F. HENDERSON, a citizen of the United States, residing at Middleton, in the county of Essex and State 5 of Massachusetts, have invented new and useful Improvements in Surgical Patches, of which the following is a specification.

This invention has for its object to provide a surgical patch of improved construction, adapted to be conveniently and securely applied to an area to be protected, and to present to a wounded or diseased portion of said area, a facing of absorbent compressible ventilating material, such as 10 absorbent cotton, to permit ventilation of the said portion.

The invention is embodied in the improvements which I will now proceed to describe and claim.

20 Of the accompanying drawings forming a part of this specification,—

Figure 1 is a plan view showing an elongated patch strip embodying the invention, adapted to be cut into a plurality of operative patches, and provided with a detachable and discardable covering layer.

Figure 2 is an enlarged section on line 2-2 of Figure 1.

Figure 3 is an enlarged plan view of a 30 patch cut from the strip shown by Figure 1, the covering layer being removed.

Figure 4 is a section on line 4-4 of Figure 3.

Figure 5 is a view similar to Figure 4, 35 showing the patch applied to an area to be protected.

Figure 6 is a view similar to Figure 3, showing a single patch provided with a detachable and discardable covering layer.

40 Figure 7 is a plan view of an elongated patch strip, and illustrating a different arrangement of the absorbent material.

The same reference characters indicate the same parts in all of the figures.

45 12 represents a confining layer of any suitable flexible sheet material, such as cotton cloth, having on its inner side an adhesive coating 13, indicated by the heavy black line in Figures 2, 4, and 5, and by the 50 transversely shaded portions in the other figures.

The said coating is of a non-drying nature, so that it remains for a protracted period in a viscous or sticky condition, a suitable material for the coating being Z. O.

plaster, an adhesive composition containing zinc oxide.

The layer 12 includes a central portion provided with apertures 14, and imperforate portions projecting in opposite directions 60 from the apertured central portion. 16 represents an absorbent layer of compressible material, which is pervious to air, such as the well known absorbent cotton. Said absorbent layer is of smaller area than the confining layer, and is united by the coating 13 to the apertured central portion of the confining layer. Said central portion, therefore, backs the absorbent layer, and is called a backing portion. The imperforate portions of the confining layer project from opposite edges of the absorbent layer and constitute flaps having adhesive inner surfaces, which are exposed, so that they may be caused to adhere to human skin. As 65 shown by Figure 5, the patch may be secured by the exposed portions of the coating 13 to an area 17, to be protected by the patch, a wound or an infected spot in said area being protected and ventilated by the 70 absorbent layer 16, and by the apertures in the central portion of the confining layer.

The inner side of the patch is formed partly by the absorbent layer 16, and partly by the inner sides of the projecting portions 85 or flaps of the confining layer 12, so that the inner side of the patch has a central absorbent ventilating section adapted to contact directly with an area to be protected, and adhesive flaps or sections at opposite edges 90 of the absorbent section adapted to adhere to skin surfaces at opposite sides of the protected area. The outer side of the patch is formed entirely by the confining layer 12, the apertures 14 of which expose portions 95 of the absorbent material to the air, so that the protected area is continuously ventilated.

When the patch is prepared for the market and kept in stock, it is preferably provided with a covering layer 18, of thin muslin, detachably secured to the patch by the exposed portions of the coating 13. When the patch is to be used, the covering layer is 100 pulled off and discarded.

I prefer in practicing my invention, to 105 manufacture an elongated surgical patch strip, as shown by Figure 1, said strip being adapted to be transversely cut as at the dotted line x-x (Figure 1), to form a plurality of independent patches. In said patch strip 110

the several layers are elongated, and the perforations in the confining layer are arranged to form a perforated longitudinal zone.

5 The strip including the elongated covering layer 18 may be rolled, folded, or otherwise prepared for the market.

In the embodiment of the invention shown by Figures 1, 3 and 6, the compressible absorbent layer extends continuously between 10 two opposite edges of the patch, so that the exposed portions of the adhesive coating 13 do not surround the facing, but are arranged at two opposite edges thereof. The absorbent material may, however, be formed and 15 arranged as shown by Figure 7, so that in an operative patch, formed for example, by cutting a patch strip on the line $x'-x'$ (Figure 7), the exposed portion of the coating 13 will entirely surround the absorbent layer 16^a, so that provision is made for causing 20 the adhesion of the confining layer at each of its edge portions.

In making up a divisible elongated patch strip, I apply a plurality of absorbent sections 16^a to the elongated confining layer 12,

the orifices 14 being arranged in groups, each group communicating with a facing section.

I claim:

A surgical patch composed of an outer layer of flexible sheet-like material provided with a series of perforations, and a layer of absorbent material, of less area than the outer layer, arranged across the inner face of the perforated section of the outer layer 35 and forming a portion of the inner side of the patch, portions of the inner surface of the outer layer beyond the margin of the absorbent layer being coated with an adhesive whereby the patch may be secured in operative position with the entire inner surface of the absorbent layer in contact with an area to be protected, the absorbent layer being 40 pervious to air and the perforations in the outer layer exposing portions of said absorbent layer to the air.

In testimony whereof I have affixed my signature.

ALBERT F. HENDERSON.
